CAR WHEEL GRINDING MACHINE

Carl G. Flygare and Herbert A. Silven, Worcester,
Mass., assignors to Norton Company, Worcester,
Mass., a corporation of Massachusetts

Application March 18, 1942, Serial No. 435,214

6 Claims. (Cl. 51—165)

The invention relates to grinding machines, and more particularly to a gauging device for a car wheel grinding machine.

One object of the invention is to provide a double head grinding machine with a visible indicating type gauging apparatus whereby two spaced portions of a work piece may be readily ground to the same diameters. Another object of the invention is to provide a double head car wheel grinding machine with a visible type gauging apparatus. Another object of the invention is to provide an electrically actuated visible gauging apparatus for a car wheel grinding machine. Another object of the invention is to provide a gauging apparatus for a car wheel grinder whereby a pair of spaced car wheels may be readily ground to the same diameters. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings in which is shown one of the various possible embodiments of the mechanical features of the invention,

Fig. 1 is a plan view of a car wheel grinding machine embodying this invention;

Fig. 2 is a fragmentary rear elevation of the car wheel grinding machine, on a slightly reduced scale;

Fig. 3 is a cross sectional view, on an enlarged scale, taken approximately on the line 3—3 of Fig. 2;

Fig. 4 is a fragmentary cross sectional view, on an enlarged scale, taken approximately on the line 4—4 of Fig. 2;

Fig. 5 is a fragmentary longitudinal sectional view through the right-hand end thrust member, as shown in Fig. 1;

Fig. 6 is a fragmentary end elevation, partly in section, on an enlarged scale, taken approximately on the line 6—6 of Fig. 1, showing one of the visible gauging units and the electric wiring diagram therefor;

Fig. 7 is a fragmentary sectional view, on an enlarged scale, taken approximately on the line 7—7 of Fig. 6; and

Fig. 8 is a fragmentary sectional view taken approximately on the line 8—8 of Fig. 6, showing the contour gauging device.

A car wheel grinding machine has been illustrated in the drawings, comprising a base 10

which serves as a support for a pair of spaced rotatable grinding wheels 11 and 12 which are mounted upon wheel slides 13 and 14, respectively. An electric motor 15 is mounted on the upper surface of the wheel slide 13 and is provided with a multiple V-groove pulley 16 which is connected by multiple V-belts 17 with a multiple V-groove pulley 18 mounted on the left-hand end of a rotatable wheel spindle 19. The wheel spindle 19 supports the grinding wheel 11 at its right-hand end (Fig. 1).

Similarly, an electric motor 20 is mounted on the upper surface of the wheel slide 14. The motor 20 is provided with a multiple V-groove pulley 21 which is connected by multiple V-belts 22 with a multiple V-groove pulley 23 which is mounted on the right-hand end of a rotatable wheel spindle 24 the other end of which supports the grinding wheel 12. The wheel spindles 19 and 24 are journaled in suitable bearings (not shown) mounted in the wheel slides 13 and 14, respectively.

A manually operable traversing mechanism is provided, including a rotatable hand wheel 25 which is connected to actuate a nut and screw mechanism (not shown) to traverse the wheel slide 13 longitudinally to produce a relative longitudinal movement between the grinding wheel 11 and the work piece to be ground.

30 A manually operable feeding mechanism is provided comprising a rotatable hand wheel 26 which is operatively connected to actuate a nut and feed screw mechanism (not shown) which are arranged to feed the wheel slide 13 and grinding wheel 11 transversely to feed the wheel toward or from the axis of the work piece to be ground as desired.

Similarly, a manually operable hand wheel 27 is operatively connected to actuate a nut and screw mechanism (not shown) to traverse the wheel slide 14 longitudinally to impart a relative longitudinal movement to the grinding wheel 12 to traverse it longitudinally relative to the work piece to be ground. A manually operable feed wheel 28 is operatively connected to a nut and screw mechanism (not shown) which are arranged to impart a transverse feeding movement to the wheel slide 14 and grinding wheel 12 to move the same toward and from the work axis so as to produce the desired grinding action.

The grinding wheel traversing and feeding mechanism for the wheel slides 13 and 14 have not been illustrated in detail since they are not considered to be a part of the present invention. 55 These mechanisms may be substantially iden-

tical with the mechanisms shown in the expired U. S. patent to C. H. Norton, No. 869,194, dated October 22, 1907, to which reference may be had for details of disclosure not contained herein.

A rotatable work support is provided for rotatably supporting a car wheel assembly, that is, a car wheel axle 30 having a pair of spaced car wheels 31 and 32 fixedly mounted thereon for a grinding operation. The work driving and supporting mechanism, as shown in plan view in Fig. 1, is substantially identical with that shown in the prior U. S. patent to C. H. Norton and Carl G. Flygare, No. 1,943,866 dated February 27, 1934, to which reference may be had for details of disclosure not contained herein.

The car axle assembly, comprising the axle 30 having the two spaced car wheels 31 and 32 fixedly mounted thereon, is provided with outwardly extending journals 33 and 34 and is mounted for rotation on spaced work supporting members so that the periphery of the car wheels 31 and 32 may be ground as desired. As illustrated in the drawings, the work supporting members comprise a pair of spaced V-shaped members 35 and 36 which are supported in vertically adjustable brackets 37 and 38 on the base 10.

In order that the V-shaped bearing surfaces may be aligned with the surface being supported, the V-shaped supports 35 and 36 are preferably pivotally mounted by means of trunnions 115 and 116 to the vertically adjustable members 37 and 38, respectively. It will be readily apparent from the foregoing disclosure that when the car wheel assembly is placed in the machine, the journals 33 and 34 engaging the V-block supports 35 and 36 will cause the V-blocks to rock and align their bearing surfaces with the peripheral surfaces of the journals 33 and 34, respectively, on the car axle 30.

A car wheel grinding machine of the type illustrated is particularly adapted for grinding surfaces of car wheels after they have been used, to eliminate the worn surface having flats and other irregularities due to uneven wear. The journals 33 and 34 of successive car wheel assemblies vary in size, due to wear in use of the assembly and also due to the amount of grinding which has heretofore taken place. It is, therefore, desirable that a suitable adjusting mechanism be provided for adjusting the ends of the car axle assembly vertically so that the axle of the car wheel assembly may be moved to coincide with the axis of the rotating driving member.

The vertically adjustable supporting members 37 and 38 are provided with guide rods 39 and 40 which slide within corresponding apertures in brackets 41 and 42, respectively. The guide rods 39 and 40 serve to hold the members 37 and 38 in proper alignment. A suitable clamping device is provided, comprising clamping screws 43 for locking the guide rods 39 and 40 in a fixed position with relation to the brackets 41 and 42, respectively, after the V-shaped bearing supports 35 and 36 have been adjusted.

The members 37 and 38 carry a depending screw threaded member 44 which meshes with a rotatable nut 45 supported within the brackets 41 and 42. The threaded bushings 45 are provided at their upper ends with a bevelled gear 46 which meshes with a bevelled gear 47 on a horizontally extending shaft 48. The outer end of the shaft 48 is provided with a manually operable hand wheel 49 by means of which the operator

may raise or lower the V-shaped supporting members 35 and 36 as desired.

In driving a pair of opposed car wheels mounted on an axle, it is necessary that the axle be held against endwise movement, since it is necessary to grind up to and adjacent the flange on the car wheel. To prevent endwise movement of the axle 30, suitable anti-friction bearing members 50 and 51 are supported on spaced brackets 52 and 53, respectively. The bearing member 52 is provided with a readily accessible adjusting screw 54 which may be turned by means of a hand wheel 55 and adjusted to position the car axle 30 in proper relationship for grinding. A screw 54 meshes with a thread extending longitudinally within a spindle 56 which may be clamped in adjusted position by means of the clamping screw 57. For further details as to the construction and operation of these anti-friction end thrust members, reference may be had to the prior U. S. patent to Norton, No. 869,194 above referred to.

In grinding work of this type, it is necessary that the work be driven by the center portion of the axle 30 between the car wheels 31 and 32. As illustrated in the drawings, this driving member may comprise a supporting frame 60 carrying a hollow spindle 61 which is held in place by the partial cylindrical caps 62 and 63. The spindle 61 carries at its left-hand end (Fig. 1) a driving gear 64 which is fixedly mounted on the spindle 61. The gear 64 and the spindle 61 are provided with a substantially U-shaped slot or aperture 65 which extends from the periphery of the gear 64 and the spindle 61 to the center of the same so that, as shown in Fig. 3, the car axle 30 may be readily dropped into position with its axis coinciding with the axis of the driving spindle 61 and gear 64. The gear 64 is provided with a plurality of spaced brackets 66 each of which carries a clamping screw 67 which are equally spaced to engage the axle 30 so as to transmit a rotary motion from the driving gear 64 to the axle 30 and the car wheels 31 and 32 during the grinding operation.

A pair of spaced driving pinions 70 and 71 are mounted on shafts 72 and 73, respectively. The shafts 72 and 73 carry driving gears 74 and 75 which mesh with a single driving pinion 76 on a shaft 77. The shaft 77 carries a worm gear 78 which meshes with a worm 79 formed on a drive shaft 80. The outer end of the shaft 80 is provided with a multi-V-groove pulley 81 which is connected by multiple V-belts 82 with a multi-V-groove driving pulley 83 carried by an electric motor 84. The spaced pinions 70 and 71 are arranged so that one of the pinions 70-71 is always in mesh with the driven gear 64 so that when the U-shaped gap 65 turns so that the teeth of the pinion 71 (Fig. 3) run out of mesh with the driven gear 64, the driving pinion 70 is in mesh and continues a uniform rotation of the gear 64. Before the U-shaped slot 65 rotates so that the teeth of the driving pinion 70 run out of mesh, the driving pinion 71 again meshes and continues the rotation of the driven gear 64 and the spindle 61. This driving arrangement eliminates the necessity of providing a gear segment to close the U-shaped slot 65, thereby saving the loss of time necessitated by inserting and removing a gear segment before and after a loading operation so as to increase the efficiency of the machine.

In the grinding and regrinding of car wheels, that is, a pair of spaced car wheels 31 and 32

which are fixedly mounted on a car axle 30, it is desirable that they be ground to true circular contour and of the same diameters, the actual size of the wheel being of a minor factor. In order to facilitate the grinding of the car wheels to equi-diameters, it is desirable to provide a visible gauging device whereby the wheels may be simultaneously ground and in which if one wheel is reduced to size and contour, a visible indication thereof serves as a signal to stop the grinding on one car wheel while grinding proceeds on the second wheel until it also is reduced to an equal size. The gauging device may comprise a shaft 85 which is supported by brackets 86 and 87 which are fixedly mounted relative to the machine base 10. The shaft 85 serves as a support for a pair of spaced gauging devices which are arranged to engage and gauge the car wheels 31 and 32 during a grinding operation.

These gauging devices comprise feeler arms 88 and 89 which are supported by needle bearings on the shaft 85. The feeler arms 88 and 89 are provided with a car wheel engaging or contacting element 90 and 91, respectively. These contacting elements 90 and 91 may be of an extremely hard substance such as, for example, a diamond to eliminate the element of wear during the grinding operation. A pair of arms 92 and 93 are respectively yoked around or straddle the hub portion of the feeler arms 88 and 89, respectively. The arms 92 and 93 are clamped in adjusted position on the shaft 85. A pair of counterbalanced or weighted arms 94 and 95 are adjustably clamped to the shaft 85 adjacent to the arms 92 and 93, respectively. The counterbalance arms 94 and 95 are arranged to counterbalance the weight of the feeler arms 88 and 89 and also the arms 92 and 93 so as to maintain the contact elements 90 and 91, respectively, in operative engagement with the peripheries of the car wheels 31 and 32, respectively. Both of the gauging devices are identical in construction, consequently only one of these devices has been illustrated in detail in Figs. 6, 7 and 8. The lower end of the arm 93 is a hollow box-like member 100 which serves to enclose and adjustably support a normally open limit switch 101. The switch 101 is supported on a plate 102 which is arranged so that it may be adjusted vertically by means of threaded bushings 103 and 104 and clamped in adjusted position by means of clamping screws 105 and 106, respectively.

An actuating plunger 107 is slidably mounted in a hub portion 108 extending upwardly from the housing 100. A compression spring 109 serves normally to hold the plunger 107 in an uppermost position so that the limit switch 101 is normally open. The electric power is supplied from any of the well-known sources, such as is illustrated diagrammatically by the power lines 110. An electric light bulb 111 is connected in series with the limit switch 101 so that when the switch is closed in a manner to be hereinafter described, the light bulb 111 will be illuminated visibly to warn the operator that the car wheel has been ground to the desired and predetermined size. A compression spring 112 is interposed between the housing 100 and the arm 89. The spring 112 surrounds a screw 113 which is rotatably and slidably adjustable within a threaded sleeve 114. The spring 112 is interposed between the under side of the threaded bushing 114 and a washer 115 which surrounds the screw 113 and bears against the upper surface of a projection 116 of the housing 100. A pair of nuts 117 on the screw 113 serve

to limit the upward movement of the arm 89 under the compression of the spring 112.

5 A stop screw 118 is screw threaded through the arm 89 and is arranged in the path of the actuating plunger 107. A lock nut 119 is provided to lock the screw 118 in adjusted position. An identical gauging device is provided in connection with the feeler arm 88, the limit switch arm 92, and the counterbalance arm 94. Consequently this structure has not been illustrated in detail since reference may be had to the disclosure contained in Figs. 6, 7 and 8.

10 After a grinding operation has been completed, the counterbalance arms 95 are lifted so that the gauging devices may be left in an inoperative position while the ground car wheel assembly is removed from the machine and a new assembly inserted there instead. A latching arm 120 is pivotally supported by a stud 121 on the counterbalance arm 95. When the counterbalance arm 95 is raised, that is, moved in a counterclockwise direction (Fig. 6), the latch arm 120 will swing under the influence of gravity into position 120a with the end of the latch arm 120 resting on a

25 stop surface 122 on the base 10. Assuming that the car wheels 32 and 31 are of different diameters, the bracket or arm 93 moves upwardly due to the counterbalance lever 95. The feeler arm 89 moves upwardly, that is, in a clockwise direction with the bracket or arm 93 due to the spring 112 until one of the contact elements 91 or 90 carried by the feeler arms 89 and 88, respectively, contacts the largest diameter car wheel and the spring 112 compresses and the lever or feeler arm 89 makes contact with the bracket or arm 93 through the adjusting screw 118 and causes a downward movement of the switch actuating plunger 107 to close the limit switch 101 which lights the electric light bulb 111 in front of the operator. The lighting of the first electric light bulb indicates the largest diameter car wheel. The grinding operation continues on the larger diameter wheel by manipulation of the wheel feeding mechanism until the limit switch 101 on the other sizing or gauging head is closed to light the second electric light bulb. When both of the lights are lit, a visible indication is imparted to the operator that both of the car wheels 32 and 31 have been ground to identical diameters.

30 45 The peripheral surface of a car wheel, as indicated, is not a true cylindrical surface but is slightly tapered, consequently it is essential that the gauging contact elements 90 and 91 engage the respective car wheels in the same relative positions, that is, on an identical taping line around the car wheel. In order to facilitate setting up the gauging devices, a profile gauge 125 is provided which may be set in a predetermined position on the feeler arm 89. The feeler arm 89 together with the bracket or arm 93 may then be adjusted longitudinally relative to the supporting shaft 85 until the profile gauge is aligned with the contour on the car wheel. When both of the gauging heads have been adjusted in this manner, the contact elements 90 and 91 will be positioned to engage the car wheels 31 and 32 in the same respective positions.

35 50 55 60 65 70 75 The operation of the improved car wheel grinding machine will be readily apparent from the foregoing disclosure. Assuming a car wheel assembly, comprising the axle 30 together with the car wheels 31 and 32 fixedly supported thereon, is mounted in an operative position on the supports 35 and 36 and the end thrust members 50 and 51 adjusted to take up the end thrust of the

axle 30, the grinding operation may proceed. The operator may manually feed the grinding wheels 11 and 12 toward the car wheels 31 and 32, respectively, by manual manipulation of the hand feed wheels 26 and 28, respectively. After a preliminary grinding operation during which operation any flats on the car wheel peripheries are removed, the latch arm 120 may be removed from positions 120a so that the counterbalance arms 94 and 95 will swing the brackets or arms 93 and 92, respectively, in a clockwise direction (Fig. 6) similarly to swing the feeler arms 89 and 88 in a clockwise direction. Unless both of the car wheels 31 and 32 are ground to the same diameters, one of the contact elements 91 or 90 will engage the larger diameter car wheel and the light bulb 111 or 111a will be illuminated, thus visibly indicating to the operator that the other car wheel, that is, the car wheel 31 is the smaller in diameter.

Assuming the car wheel 31 to be smaller in diameter than the car wheel 32, the contact element 91 will engage the larger diameter car wheel 32 and due to the counterbalance arm 95 tending to rotate the shaft 85, the spring 112 will be compressed by the swinging of the arm 93 into the position illustrated in Fig. 6 to close the limit switch 101 so as to close the circuit to illuminate the electric light bulb 111. This indicates to the operator that the wheel 32 is larger in diameter than the car wheel 31. The operator then stops the infeeding movement of the grinding wheel 11 and continues actuation of the feed wheel 28 to feed the grinding wheel 12 to grind the car wheel 32 to a smaller size or diameter. When the car wheel 32 has been ground to the same size or diameter as the car wheel 31, the contact element 90 will engage the periphery of the car wheel 31, thus actuating the second normally open limit switch to close a circuit and illuminate the electric light bulb 111a, indicating to the operator that the car wheel 32 has been ground to the same diameter as the car wheel 31, thus completing the grinding operation. As previously mentioned, in the grinding of car wheels, either the new wheel or a reground wheel, the contour of the wheel peripheries and equal diameters of each pair of car wheels is essential.

While this invention, as above described, is applicable to facilitate the grinding of car wheels, it will be readily apparent that it is equally applicable in grinding other work pieces having two spaced portions to be ground to the same or different diameters.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

We claim:

1. In a car wheel grinding machine having a base, a rotatable support for a car wheel assembly including an axle and two spaced car wheels thereon, a pair of spaced rotatable grinding wheels, an independent longitudinal traversing mechanism for each of said wheels, an independent wheel feeding mechanism independently to feed each of said wheels transversely to grind the peripheries of said car wheels, and a size indicat-

ing device including a rock shaft, a pair of adjustably spaced feeler arms thereon each having a work engaging contact point, a normally open limit switch associated with each of said feeler arms which are arranged to be closed by movement thereof, an electric light bulb connected in series with each of said switches, and a counterbalance mechanism for said arms and switches whereby the feeler arms may be moved toward the surfaces of the car wheels being ground, said feeler arms being arranged so that one of them may be moved into operative engagement with the car wheel after a preliminary grinding operation to indicate a difference in diameter of the wheels so that the larger diameter wheel may be readily reduced to the size of the smaller diameter wheel by manipulation of the feeding mechanism.

2. In a grinding machine having a base, a rotatable work support for a work piece having two spaced portions thereon to be ground to equal diameters, a pair of spaced rotatable grinding wheels, an independent longitudinal traversing mechanism for each of said wheels, an independent wheel feeding mechanism independently to feed each of said wheels transversely, and a size indicating device comprising a rock shaft, a pair of adjustably spaced feeler arms thereon each having a work engaging contact point, a normally open limit switch associated with each of said feeler arms which are arranged to be closed by movement thereof, an electric light bulb connected in series with each of said switches, and a counterbalance mechanism for said arms and switches whereby the feeler arms may be moved and maintained in operative engagement with the work piece, said feeler arms being arranged so that they may be moved into operative engagement with the work surfaces after a preliminary grinding operation to indicate a difference in diameter of the work portions so that the large diameter portion may be readily reduced to size by manipulation of the feeding mechanism.

3. In a car wheel grinding machine having a base, a rotatable work support for a car wheel assembly including an axle and two spaced car wheels thereon, a pair of spaced rotatable grinding wheels, an independent longitudinal traversing mechanism for each of said wheels, an independent wheel feeding mechanism independently to feed each of said wheels transversely to produce a grinding operation, a size indicating device therefor including a pair of adjustably spaced feelers which are movable toward and from the peripheries of said spaced car wheels, a visible indicator associated with each of said feelers, one of said indicators being arranged visibly to indicate the larger diameter car wheel after a preliminary grinding operation, the other of said indicators being arranged visibly to indicate when the larger diameter car wheel has been ground to the diameter of the smaller, and means to maintain said size indicating device in an inoperative position during a preliminary grinding operation.

4. In a car wheel grinding machine having a base, a rotatable work support for a car wheel assembly including an axle and two spaced car wheels thereon, a pair of spaced rotatable grinding wheels, an independent longitudinal traversing mechanism for each of said wheels, an independent wheel feeding mechanism independently to feed each of said wheels transversely to produce a grinding operation, a size indicating device therefor including a pair of adjustably

spaced feelers which are movable toward and from the peripheries of said spaced car wheels, a visible indicator associated with each of said feelers, one of said indicators being arranged visibly to indicate the larger diameter car wheel after a preliminary grinding operation, the other of said indicators being arranged visibly to indicate when the larger diameter car wheel has been ground to the diameter of the smaller, and a latch to maintain said size indicating device in an inoperative position during a preliminary grinding operation.

5. In a car wheel grinding machine having a base, a rotatable work support for a car wheel assembly including an axle and two spaced car wheels thereon, a pair of spaced rotatable grinding wheels, an independent longitudinally traversing mechanism for each of said wheels, an independent wheel feeding mechanism independently to feed each of said wheels transversely, and a size indicating device therefor including a rock shaft supported in brackets on the machine base, an arm adjustably clamped to said shaft, a housing within said arm, a normally open limit switch within said housing, an electric light bulb connected in series with said switch visible to indicate the size of a car wheel, a feeler arm pivotally mounted on said shaft having a work engaging contact element, an adjustably mounted stop screw on said feeler arm which is arranged to actuate said switch, a compression spring normally to hold said arm and feeler arm apart, and a counterbalance arm adjustably supported on said rock shaft to counterbalance said arms to move said feeler arm into operative contact with a work piece.

10 6. In a car wheel grinding machine having a base, a rotatable work support for a car wheel assembly including an axle and two spaced car wheels thereon, a pair of spaced rotatable grinding wheels, an independent longitudinally traversing mechanism for each of said wheels, an independent wheel feeding mechanism independently to feed each of said wheels transversely, and a size indicating device therefor including 15 a rock shaft supported in brackets on the machine base, a pair of spaced arms adjustably clamped on said shaft, a housing within each of said arms, a normally open limit switch within each of said housings, an electric light bulb connected in series with each of said switches visibly to indicate the relative size of said car wheels, a pair of spaced feeler arms pivotally mounted on said shaft each having a work engaging contact element, an adjustably mounted stop on each of said feeler arms which are arranged to actuate said switches, a compression spring normally to hold said arms and feeler arms apart, and a counterbalance arm adjustably supported on said rock shaft to counterbalance said arms, said size indicating device being arranged so that one of 20 said electric light bulbs is illuminated after a preliminary grinding operation to indicate the larger diameter car wheel, the other of said electric light bulbs being arranged to be illuminated visibly to indicate when the larger diameter car wheel has been ground to the same diameter as the smaller car wheel.

CARL G. FLYGARE.
HERBERT A. SILVEN.
